UNITED STATES PATENT OFFICE.

EDWARD A. TURNER, OF CHICAGO, ILLINOIS.

DEVICE FOR GOLF-HOLES.

SPECIFICATION forming part of Letters Patent No. 621,390, dated March 21, 1899.

Application filed December 27, 1898. Serial No. 700,318. (No model.)

To all whom it may concern:

Be it known that I, EDWARD A. TURNER, a citizen of the United States, residing at Chicago, in the county of Cook and State of Illinois, have invented a certain new and useful Improvement in Devices for Golf-Holes, of which the following is a specification.

My invention relates to devices for golf-holes, and has for its object to provide a new and improved device for this purpose.

My invention is illustrated in the accompanying drawings, wherein—

Figure 1 is a side elevation showing a device embodying my invention in position. Fig. 2 is a longitudinal section through Fig. 1. Fig. 3 is a longitudinal section similar to Fig. 2, showing a modified construction.

Like letters refer to like parts throughout the several figures.

In playing the game of golf golf-links are laid out and provided with a series of holes located at different parts of the link. The ball is then successively deposited in these holes in accordance with the rules of the game. These holes, besides receiving the balls, are adapted to receive a suitable marking device, usually called a "hole-marker," the purpose of which is to aid the player in locating the hole when he is at a distance from it. The ground around each golf-hole for a short distance is usually made level and the grass cut short, so as to facilitate the operation of the player in depositing the ball in the hole. This level space is generally called the "putting-green." When the player is at a distance from the hole, the location of the hole is made known by the hole-marker, and when he reaches the putting-green the marker is removed from the hole, so that the ball will not be obstructed by it. After the ball is deposited in the hole it is removed therefrom and the marker again placed therein, the player going on to the next hole.

The object of my invention is to provide a new and improved device for receiving the golf-ball, said device so constructed as to insure the proper insertion of the hole-marker therein without the exercise of any care by the person inserting it and at the same time to hold the hole-marker in a proper upright position, so that it will accurately mark the location of the hole.

In the accompanying drawings I have shown one construction embodying my invention. This construction comprises an outer wall portion A, which in the drawings is illustrated as cylindrical and which is adapted to be placed in the hole in the ground. Associated with said wall portion A is an inclined or funnel-shaped bottom B, provided with an opening C to receive the end portion of the hole-marker, said bottom being provided with a projecting part D, through which the opening C passes. When the device is in position, the ball is received within the cylindrical part 55 and rests upon the inclined bottom B. When it is desired to place the hole-marker in the hole, the end portion of the marker is dropped into the cylinder and the inclined bottom insures this end portion being received into the opening C. The projecting part D, being of some length, provides sufficient engaging surface for the hole-marker to insure its being held in an upright position. As the hole-marker is usually placed in the hole by a 60 "caddie," who is hurrying to get off the putting-green, it is usually placed therein in a hasty careless manner, and when the holes heretofore used are employed is generally left standing in an inclined position, and 65 hence is not as easily seen at a distance. When my device is used, it matters not how carelessly the hole-marker is inserted in the hole the end portion thereof will pass into the opening C, and the hole-marker will thus be 70 held in a proper upright position.

In Fig. 2 I have shown the bottom B and associated parts as integral with the cylindrical part C and as formed into what may be termed a "thin partition or funnel." It is 75 of course evident that this construction may be varied, if desired, without departing from the spirit of my invention, as I have only attempted to show a construction which would make my invention clear. Instead of making the bottom integral with the cylindrical part I may make it separate and attach it in any desired manner, as by means of the bolts or rivets E. (See Fig. 3.) When my device is used, it will be seen that a clean receptacle 80 is provided for the ball, such receptacle being free from the mud and dirt usually found in golf-holes.

I prefer to cast the device in the form illus-

- trated in Figs. 1 and 2; but it is of course evident that the device may be formed in any desired manner and the construction and arrangement varied, as may be desired. When 5 constructed as herein shown with the funnel-shaped bottom, less material is used and a lighter device is obtained than would be obtained if the bottom were made of a different form.
- 10 When the device is made in one piece of cast-iron or other cast metal, as illustrated in Figs. 1 and 2, there is obtained a solid durable construction, which is not injured or bent or otherwise distorted by the careless 15 handling of the hole-marker.
- I claim—
1. A device for golf-holes, comprising an outer wall portion, an inclined bottom associated with said outer wall portion, said bottom located between the extremities of the wall portion and provided with an opening adapted to receive the end portion of the hole-marker.
  2. A device for golf-holes, comprising an outer wall portion, an inclined bottom associated therewith and provided with an opening adapted to receive the end portion of the hole-marker, said opening so positioned that the incline of the bottom insures the insertion of the end portion of the hole-marker therein, when said end is placed in the golf-hole, said opening provided with an extended engaging wall or face for engaging the end portion of the hole-marker and supporting it laterally.
  3. A device for golf-holes, comprising an outer wall portion provided with a funnel-shaped bottom adapted to support the ball,

said funnel-shaped bottom open at the end and formed at its lower extremity so as to engage the end portion of the hole-marker, when said hole-marker is inserted in the golf-hole, and hold it in place.

4. A device for golf-holes, comprising an outer wall portion provided with a funnel-shaped bottom adapted to support the ball, said funnel-shaped bottom open at the end and formed at its lower extremity with an extended engaging face or wall adapted to engage the end portion of the hole-marker, so as to hold said hole-marker in an upright position.

5. A device for golf-holes, comprising an outer wall portion of cast metal, an inclined bottom for supporting the ball integral with said outer wall portion and provided with an elongated opening extending through the bottom and adapted to receive and support the end portion of the hole-marker, the entire device cast in one piece so as to form a solid durable unitary structure.

6. A device for golf-holes, comprising a cylinder of cast metal, a funnel-shaped bottom or partition contained within said cylinder and connected therewith intermediate or between the ends of said cylinder, said funnel-shaped bottom or partition cast integral with said cylinder and formed at its lower extremity so as to engage the end portion of the hole-marker at different points along its length and hold said hole-marker in an upright position.

EDWARD A. TURNER.
